CLAIM

The ornamental design for a device for remote insect capture and disposal, as shown and described.

DESCRIPTION

FIG. 1 is an upper right perspective view of the device for remote insect capture and disposal showing the new design, with one disposable disk magnetically attached to its bottom;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines depict environmental structure and are included for the purpose of illustrating only and form no part of the claimed design.
